DESIGN FOR AN AIR CONDITIONING CONTROL

Ernoll W. La Barre, New York, N. Y., assignor to
Bendix Aviation Corporation, Baltimore, Md., a
corporation of Delaware

Application May 21, 1946, Serial No. 129,945

Term of patent 7 years

(Cl. D52—7)

To all whom it may concern:

Be it known that I, Ernoll W. La Barre, a citizen of the United States, residing in the city of New York, in the county of New York and State of New York, have invented a new, original, and ornamental Design for an Air Conditioning Control, of which the following is a specification, reference being had to the accompanying drawing, forming part thereof, and in which

Figure 1 is a perspective view of an air conditioning control embodying my new design looking from a point above and to the left; and

Figure 2 is a perspective view of the same looking from a point below and to the right.

I claim:

The ornamental design for an air conditioning control, substantially as shown.

ERNOLL W. LA BARRE.
